ABSTRACT: An improved keyslot bearing contour for a railroad coupler shank is disclosed. The keyslot contour comprises a plurality of arcs which are designed to minimize localized bearing on the keyslot during angular pull of the coupler. The improved keyslot contour is formed by a first arc, rearwardly extending towards the butt end of the coupler, which terminates in a plurality of second arcs located at each side of the coupler in proximity to the intersection of the keyslot with the side walls of the coupler.

COUPLER KEYSLOT BEARING CONTOUR

BACKGROUND OF THE INVENTION

This invention relates generally to railroad couplers and more particularly to an improved coupler keyslot bearing contour which minimizes localized keyslot bearing during angular pulling on the coupler.

In a standard railroad-type E-coupler having a horizontal key, the key bearing surface of the coupler is generally cylindrical shaped and is located with its axis perpendicular to the longitudinal axis of the coupler shank. Under service buffing conditions the load on the coupler is transmitted through the butt end of the coupler with the key remaining unloaded.

Under service pulling conditions, the load is transmitted to the yoke and draft gear through the key. When the coupler is straight, this load is distributed over the entire length of the cylindrical key bearing surface. However, when the coupler is horizontally angled, the key is also angled in the coupler shank keyslot resulting in the load being transmitted on a corner of the keyslot at the intersection of the keyslot with the sidewall of the coupler. This results in a severe peening action at this intersection which may cause cracks to occur and material failures to result in the coupler shank.

SUMMARY OF THE INVENTION

The present invention overcomes the beforementioned difficulties and limitations by providing an improved coupler keyslot bearing surface which minimizes the localized bearing on the keyslot bearing surface during an angular pull on the coupler.

Accordingly, it is the object of the invention to provide a new and novel improved coupler keyslot bearing contour for a railroad coupler shank which provides substantially constant stress patterns to minimize localized bearing on the keyslot bearing surface during angular pull on the coupler.

Another object of the invention is to provide new and novel improved coupler keyslot bearing contour having an improved bearing surface by means of the use of a plurality of intersecting arcs formed in the keyslot.

These and other objects and advantages of the invention will become apparent from a study of the attached drawings and from a reading of the description of the preferred embodiment.

BRIEF DESCRIPTION OF THE DRAWINGS

FIG. 1 is a plan view, shown partially in section, of a standard-type railroad E-coupler in a horizontally angled buffing position;

FIG. 2 is a plan view, shown partially in section, of a standard-type railroad E-coupler in a horizontally angled pulling position;

FIG. 3 is a partial sectional view of the butt end of the coupler shank showing one embodiment of the improved keyslot bearing contour of the invention;

FIG. 4 is an enlarged sectional view of FIG. 3 showing the intersection of the keyslot bearing surface with the side walls of the coupler shank; and

FIG. 5 is a side elevational view of the butt end of the coupler shank showing the keyslot of FIG. 3 with the means for forming a plurality of hereinafter described second arcs.

FIG. 6 is an enlarged sectional view of a modification of the improved keyslot bearing contour of the invention.

DESCRIPTION OF THE PREFERRED EMBODIMENT

Referring now more particularly to the drawings, there is shown generally at 10 a standard-type railroad E-coupler which comprises a coupler head 12 having attached thereto a coupler shank 14 which terminates at the butt end 16 of the coupler 10. The butt end 16 of the coupler 10 contains a horizontal keyslot 18 designed to receive a load transmitting key 20. When the coupler 10 is under the buffing condition, as shown in FIG. 1, the coupler load is transmitted through the

butt end 16 to the follower and draft gear 22 contained rearwardly of the coupler 10. In such a condition, the key 20 remains unloaded, as shown in FIG. 1, with no buffering contact load between the keyslot 18 and 20.

Referring now to FIG. 2 there is shown the standard coupler under pulling conditions wherein the coupler load is transmitted to the yoke and draft gear through the key 20 by means of the keyslot bearing surface 24. When the pull on the coupler is straight, the coupler load is distributed over the entire bearing surface 24. However, a horizontal angling of the coupler, as shown in FIG. 2, results in angularity of the key 20 in the coupler keyslot 18. Under such conditions, the coupler load is then transmitted on the corner 26 of the keyslot 18 at the location where the keyslot 18 intersects the sidewall 28 of the coupler 10 resulting in a severe peening of the corner 26 which may cause cracks and material failures to occur at this portion of the keyslot.

Referring now to FIG. 3 of the drawings there is shown the improved coupler keyslot bearing contour of the invention which comprises a first arc 30 formed rearwardly towards the butt end 16 of the coupler 10. The first arc 30 terminates in a plurality of second arcs, shown generally as the numeral 32, which terminate tangent to the sidewalls 28 of the coupler shank 14. The first arc 30 forming the key bearing surface of the keyslot 18 may be formed as an inner arc of a toroid having a radius lying rearwardly from the butt end 16 of the coupler shank 14.

In the embodiment shown a radius of substantially 50 inches would encompass the normal range of the coupler angling to provide a substantially constant stress pattern in the bearing surfaces to the corner 26.

Referring now to FIG. 4 in particular, there is shown in an enlarged sectional view one of the plurality of second arcs 32 of the invention. In the embodiment shown the second arcs 32 comprise a plurality of radii 34 which initiate at the terminating point of the first arc 30 and terminate tangent to the coupler sidewalls 28. In manufacturing of the improved bearing contour the plurality of second arcs 32 may be formed by means of a plurality of vertical grooves 36, one of which is shown in FIG. 5 of the drawings, at the respective sidewalls 28 of the coupler shank 14. When the second arcs 32 are formed in this manner, the possibility of undercutting of the sidewalls is eliminated should the keyslot core shift along its axis during the pouring process.

In the embodiment shown in FIG. 4 the grooves 36 are completed by a plurality of radii 38 terminating at the sidewalls 28 of the coupler shank 14. A preferred dimension for radius 34 would be substantially three-eighth of an inch and preferred dimension for the radius 38 would be substantially 1 inch.

In addition to the toroidal shape of the key bearing surface 24 of the invention, the surface may also be formed in the shape of other rearwardly extending first arcs, such as an elliptic segment, a parabolic segment or a hyperbolic segment, to name a few, all of which would terminate in the plurality of second arcs 32 without departing from the spirit and scope of the invention. When the key bearing surface is provided with the toroidal shaped arc or other arcs having rearwardly extending configurations, it can be seen that improved coupler performance is obtained during pulling conditions resulting in providing more bearing area at the corner 26 of the keyslot 18 thereby providing for coupler angularity.

Referring now to FIG. 6 there is shown a modification of the improved keyslot bearing contour of the invention wherein the second arcs of the invention are formed by the radii 40, one of which is located on each side of the coupler keyslot. The radii 40 forms the second arcs of the invention and initiate at the termination of the first arc 30 and terminate tangent to a line parallel to the coupler sidewall 28, said line lying outside the coupler sidewall.

When the second arcs are formed in this manner the plurality of grooves shown in the embodiment of FIGS. 3, 4 and 5 would not be used and in place thereof would be formed a

small amount of metal 42 outside of the sidewall 28 that could be removed by grinding. The amount of the metal 42 is sufficient to accommodate tolerances necessary in setting the core without obtaining excessive undercut of the sidewall 28 in case the keyslot core shifts along its axis during the pouring process. It has been found that when the radius 40 is approximately three-eighth of an inch that the maximum undercut of the sidewall 28 will be one-sixteenth of an inch.

From the foregoing it can be seen that an improved new and novel coupler keyslot bearing contour, as shown in the embodiment of FIG. 3 or the modification of FIG. 6, has been provided, which minimizes the localized bearing on the keyslot bearing surface during an angular pull on the coupler. This has been accomplished by the novel use of a first arc and a plurality of second arcs formed in the manner hereinbefore described. While all of the objects and advantages of the invention have been provided for in the embodiment and modification shown, it is apparent that many changes in details of construction may be made without departing from the spirit and scope of the invention, which is expressed in the accompanying claims and the invention is not to be limited to the exact matters shown and described since only the preferred embodiment has been given by way of illustration only.

I claim:

1. In a railroad coupler shank of the type having a horizontal keyslot forming a key bearing surface through the butt end of the coupler shank, the improvement comprising:

- a. the key bearing surface being formed in the shape of a rearwardly extending first arc; and
- b. a plurality of second arcs tangent to the coupler shank walls and said first arc and formed at the intersection of said first arc and the coupler sidewalls, said first and second arcs serving to minimize the localized bearing on the keyslot of the coupler shank during angular pull of the coupler.

2. The improvement as defined in claim 1 wherein said first arc comprises an inner arc of a toroid having a radius lying rearwardly from the butt end of the shank.

3. The improvement as defined in claim 1 wherein said second arcs are formed by means of the sidewalls having formed therein a plurality of vertical grooves extending the height of the sidewalls and located at the intersection of said

first arc and the sidewalls.

4. In a railroad coupler shank of the type having a horizontal keyslot forming a key bearing surface through the butt end of the coupler shank, the improvement comprising the key bearing surface being formed in the shape of a rearwardly extending elliptic segment terminating in a plurality of second arcs at the intersection of the sidewalls and the key bearing surface for minimizing the localized bearing on the keyslot during an angular coupler pull.

5. The improvement as defined in claim 4 wherein each of said second arcs are formed by a vertical groove formed in the related sidewall and located at the intersection of the key bearing surface and the related sidewall.

6. The improvement as defined in claim 4, wherein each of

15 said second arcs is defined at a portion thereof rearwardly of said segment by a pair of radii and is defined forwardly of said segment by another pair of radii longer than said first-mentioned radii.

7. In a railroad coupler shank of the type having a horizontal

20 keyslot forming a key bearing surface through the butt end of the coupler shank, the improvement comprising:

a. the key bearing surface being formed in the shape of a rearwardly extending first arc; and

b. a plurality of second arcs initiated at the termination of said first arc and terminating tangent to a line parallel to the coupler sidewall, said line lying outside of the sidewall, said first and second arcs serving to minimize the localized bearing on the keyslot of the coupler shank during angular pull of the coupler.

30 8. The improvement as defined in claim 7 wherein said first arc comprises an inner arc of a toroid having a radius lying rearwardly from the butt end of the shank.

9. In a railroad coupler shank of type having a horizontal keyslot forming a key bearing surface through the butt end of the coupler shank, the improvement comprising the key bearing surface being formed in the shape of a rearwardly extending elliptic segment terminating in at least two second arcs, located on each side of the coupler sidewall, said second arcs

35 terminating tangent to a line which lies parallel to the coupler sidewall and outside of the sidewall, said first and second arcs serving to minimize the localized bearing on the keyslot during angular coupler pull.
